ABSTRACT

Dispenser and method for dispensing sheets of material, particularly metallic foil. The dispenser houses the metallic foil in roll form, the foil having a free end which can be grasped by the beautician, cut to the appropriate length by a cutting blade, for example coupled to the dispenser housing, and applied to the hair in the conventional manner. In one embodiment of the invention, the dispenser also supports one or more containers for coloring solution or other liquids useful for the application.

FOIL DISPENSER APPARATUS AND METHOD

This application is a continuation of Ser. No. 09/005,208 filed Jan. 9, 1998 now abandoned which is a continuation in part of Ser. No. 08/927,516 filed Sep. 11, 1997 now abandoned.

BACKGROUND OF THE INVENTION

The present invention is directed towards a dispensing apparatus for metallic foil or the like, particularly applicable to that used by beauticians and hair stylists to color or highlight hair.

Several conventional processes having been in use for selectively coloring or highlighting hair. In one prior art process, a perforated cap is placed on the subject's head, with one or more locks of hair pulled through the various perforations in order to segregate them from the remainder of the hair under the cap. These selected locks of hair can then be colored by a conventional hair coloring procedure, such as by painting with hair coloring or bleaching solutions.

Another more recent approach is with the use of metallic foil, typically aluminum foil. With this procedure, the beautician isolates a lock of hair to be colored, and places the isolated lock on a pre-cut strip of foil. The hair coloring solution is then applied to the lock of hair supported on the foil such as by painting, and the treated lock of hair is then wrapped in the foil for a period of time so that the hair coloring solution can take effect. This procedure is then repeated with further locks of hair, until the desired amount of hair has been treated. In this manner, hair can be highlighted (e.g., a gradient of color from lighter to darker can be obtained), colored, bleached, etc.. Wax paper can also be used instead of metallic foil.

However, it is readily apparent that the foregoing procedure is tedious, cumbersome and time consuming. Generally the foil or paper used must be pre-cut into strips of the appropriate size, and laid out for the beautician so that they are readily accessible during the coloring procedure. In addition, where multiple colors are employed in a single coloring operation, the containers or bowls housing these liquid coloring solutions have a tendency to spill.

Accordingly, it would be desirable to provide apparatus and a method for successively dispensing metallic foil or paper, thereby providing ready and easy access to the foil or paper without pre-cutting.

SUMMARY OF THE INVENTION

The problems of the prior art have been overcome by the present invention, which provides a dispenser and method for dispensing sheets of material, particularly metallic foil. The dispenser houses the metallic foil in roll form, the foil having a free end which can be grasped by the beautician, cut to the appropriate length by severing means coupled to the dispenser housing, and applied to the hair in the conventional manner. In one embodiment of the invention, the dispenser also supports one or more containers for coloring solution or other liquids useful for the application.

BRIEF DESCRIPTION OF THE DRAWINGS

FIG. 1 is a side view of one embodiment of the present invention;

FIG. 2 is a perspective view of the embodiment of FIG. 1;

FIG. 3 is a perspective view of the embodiment of FIG. 1 in an open or install position;

FIG. 4 is a perspective view of a second embodiment of the present invention;

FIG. 5 is a side view of the sheet material as wrapped around a comb upon dispensing from the apparatus;

FIG. 6 is a perspective view of a third embodiment of the present invention;

FIGS. 7A, 7B and 7C are perspective views showing three steps in carrying out the method using the device of the present invention;

FIG. 8 is a perspective view showing a further improvement of the embodiment shown in FIG. 1;

FIG. 9 is a perspective view showing the embodiment of FIG. 8 in use; and

FIG. 10 is a perspective view showing the embodiment of FIG. 8 in use.

DETAILED DESCRIPTION OF THE INVENTION

Turning first to FIGS. 1 and 2, there is shown one embodiment of the dispenser apparatus 10 of the present invention. The dispenser is particularly useful in dispensing metallic foil, preferably aluminum foil, in such a manner that the beautician can selectively size each individual piece by appropriately severing each individual piece from the main roll. Those skilled in the art will recognize that other sheet materials, such as wax paper, could also be used. The size and grade of the metallic foil is not particularly limited and will depend upon the particular application, but generally is between about 5-7 mils thick.

The dispenser 10, which is preferably made of steel, includes a base portion 12 having opposite side walls 40, 41 on which the metallic foil roll is rotatably mounted. In the embodiment shown, the metallic foil 50 is provided in a rolled-up fashion on a hollow cylindrical core. A cylinder 14 having an outside diameter smaller than the inside diameter of the hollow cylindrical core is adapted to be received by the hollow cylindrical core, the core being able to rotate about the cylinder 14 simply by pulling the free end of the foil 50. The cylinder 14 at its respective longitudinal ends is preferably removably fixed to the base portion 12. The manner in which the cylinder 14 is so coupled is not particularly limited, as long as the cylinder can be readily removed so that the roll of metallic foil can be easily inserted over the cylinder. The preferred means of coupling the cylinder 14 to the base 12 is by providing apertures or slots at the respective longitudinal ends of the cylinder 14, the slots be sized and shaped to receive corresponding pins 33 projecting from the base 12, and more particularly, from the side walls 40, 41. The hollow cylindrical core of the foil roll can also terminate at one or both of its longitudinal ends in a shape keyed to fit into a corresponding shape associated with the base 12 or side walls 40, 41.

Extending from the rear of the base portion 12 is a support arm 15. Preferably the support arm 15 is hinged to the base 12 via hinge mechanism 34 so that the arm 15 can be moved, thereby allowing unobstructed access to the cylinder 14 in order to install or remove the metallic foil roll from the apparatus. A stop 17 is provided coupled to base 12 so that the support arm 15 always returns to the same operative position relative to the foil roll, as shown in FIG. 1. The support arm can be locked in this position by any suitable means, such as a screw or latch (not shown). The support arm 15 terminates at its end distal from the base portion 12 in a severing device 20, preferably a sharp-tooth strip having a plurality of teeth, preferably ranging from about 15

60 to 100 teeth, which is selectively operable to sever the foil 50 from the roll. The severing device 20 is selectively operable by a lever 22 which is selectively operable by a handle 24. The lever 22 is selectively operable by a lever 26 which is selectively operable by a handle 28. The lever 26 is selectively operable by a lever 30 which is selectively operable by a handle 32. The lever 30 is selectively operable by a lever 34 which is selectively operable by a handle 36. The lever 34 is selectively operable by a lever 38 which is selectively operable by a handle 40. The lever 38 is selectively operable by a lever 42 which is selectively operable by a handle 44. The lever 42 is selectively operable by a lever 46 which is selectively operable by a handle 48. The lever 46 is selectively operable by a lever 50 which is selectively operable by a handle 52. The lever 50 is selectively operable by a lever 54 which is selectively operable by a handle 56. The lever 54 is selectively operable by a lever 58 which is selectively operable by a handle 60. The lever 58 is selectively operable by a lever 62 which is selectively operable by a handle 64. The lever 62 is selectively operable by a lever 66 which is selectively operable by a handle 68. The lever 66 is selectively operable by a lever 70 which is selectively operable by a handle 72. The lever 70 is selectively operable by a lever 74 which is selectively operable by a handle 76. The lever 74 is selectively operable by a lever 78 which is selectively operable by a handle 80. The lever 78 is selectively operable by a lever 82 which is selectively operable by a handle 84. The lever 82 is selectively operable by a lever 86 which is selectively operable by a handle 88. The lever 86 is selectively operable by a lever 90 which is selectively operable by a handle 92. The lever 90 is selectively operable by a lever 94 which is selectively operable by a handle 96. The lever 94 is selectively operable by a lever 98 which is selectively operable by a handle 100. The lever 98 is selectively operable by a lever 102 which is selectively operable by a handle 104. The lever 102 is selectively operable by a lever 106 which is selectively operable by a handle 108. The lever 106 is selectively operable by a lever 110 which is selectively operable by a handle 112. The lever 110 is selectively operable by a lever 114 which is selectively operable by a handle 116. The lever 114 is selectively operable by a lever 118 which is selectively operable by a handle 120. The lever 118 is selectively operable by a lever 122 which is selectively operable by a handle 124. The lever 122 is selectively operable by a lever 126 which is selectively operable by a handle 128. The lever 126 is selectively operable by a lever 130 which is selectively operable by a handle 132. The lever 130 is selectively operable by a lever 134 which is selectively operable by a handle 136. The lever 134 is selectively operable by a lever 138 which is selectively operable by a handle 140. The lever 138 is selectively operable by a lever 142 which is selectively operable by a handle 144. The lever 142 is selectively operable by a lever 146 which is selectively operable by a handle 148. The lever 146 is selectively operable by a lever 150 which is selectively operable by a handle 152. The lever 150 is selectively operable by a lever 154 which is selectively operable by a handle 156. The lever 154 is selectively operable by a lever 158 which is selectively operable by a handle 160. The lever 158 is selectively operable by a lever 162 which is selectively operable by a handle 164. The lever 162 is selectively operable by a lever 166 which is selectively operable by a handle 168. The lever 1092 is selectively operable by a lever 1098 which is selectively operable by a handle 1100. The lever 1098 is selectively operable by a lever 1106 which is selectively operable by a handle 1108. The lever 1106 is selectively operable by a lever 1112 which is selectively operable by a handle 1114. The lever 1112 is selectively operable by a lever 1118 which is selectively operable by a handle 1120. The lever 1118 is selectively operable by a lever 1126 which is selectively operable by a handle 1128. The lever 1126 is selectively operable by a lever 1132 which is selectively operable by a handle 1134. The lever 1132 is selectively operable by a lever 1138 which is selectively operable by a handle 1140. The lever 1138 is selectively operable by a lever 1146 which is selectively operable by a handle 1148. The lever 1146 is selectively operable by a lever 1152 which is selectively operable by a handle 1154. The lever 1152 is selectively operable by a lever 1158 which is selectively operable by a handle 1160. The lever 1158 is selectively operable by a lever 1166 which is selectively operable by a handle 1168. The lever 1166 is selectively operable by a lever 1172 which is selectively operable by a handle 1174. The lever 1172 is selectively operable by a lever 1178 which is selectively operable by a handle 1180. The lever 1178 is selectively operable by a lever 1186 which is selectively operable by a handle 1188. The lever 1186 is selectively operable by a lever 1192 which is selectively operable by a handle 1194. The lever 1192 is selectively operable by a lever 1198 which is selectively operable by a handle 1200. The lever 1198 is selectively operable by a lever 1206 which is selectively operable by a handle 1208. The lever 1206 is selectively operable by a lever 1212 which is selectively operable by a handle 1214. The lever 1212 is selectively operable by a lever 1218 which is selectively operable by a handle 1220. The lever 1218 is selectively operable by a lever 1226 which is selectively operable by a handle 1228. The lever 1226 is selectively operable by a lever 1232 which is selectively operable by a handle 1234. The lever 1232 is selectively operable by a lever 1238 which is selectively operable by a handle 1240. The lever 1238 is selectively operable by a lever 1246 which is selectively operable by a handle 1248. The lever 1246 is selectively operable by a lever 1252 which is selectively operable by a handle 1254. The lever 1252 is selectively operable by a lever 1258 which is selectively operable by a handle 1260. The lever 1258 is selectively operable by a lever 1266 which is selectively operable by a handle 1268. The lever 1266 is selectively operable by a lever 1272 which is selectively operable by a handle 1274. The lever 1272 is selectively operable by a lever 1278 which is selectively operable by a handle 1280. The lever 1278 is selectively operable by a lever 1286 which is selectively operable by a handle 1288. The lever 1286 is selectively operable by a lever 1292 which is selectively operable by a handle 1294. The lever 1292 is selectively operable by a lever 1298 which is selectively operable by a handle 1300. The lever 1298 is selectively operable by a lever 1306 which is selectively operable by a handle 1308. The lever 1306 is selectively operable by a lever 1312 which is selectively operable by a handle 1314. The lever 1312 is selectively operable by a lever 1318 which is selectively operable by a handle 1320. The lever 1318 is selectively operable by a lever 1326 which is selectively operable by a handle 1328. The lever 1326 is selectively operable by a lever 1332 which is selectively operable by a handle 1334. The lever 1332 is selectively operable by a lever 1338 which is selectively operable by a handle 1340. The lever 1338 is selectively operable by a lever 1346 which is selectively operable by a handle 1348. The lever 1346 is selectively operable by a lever 1352 which is selectively operable by a handle 1354. The lever 1352 is selectively operable by a lever 1358 which is selectively operable by a handle 1360. The lever 1358 is selectively operable by a lever 1366 which is selectively operable by a handle 1368. The lever 1366 is selectively operable by a lever 1372 which is selectively operable by a handle 1374. The lever 1372 is selectively operable by a lever 1378 which is selectively operable by a handle 1380. The lever 1378 is selectively operable by a lever 1386 which is selectively operable by a handle 1388. The lever 1386 is selectively operable by a lever 1392 which is selectively operable by a handle 1394. The lever 1392 is selectively operable by a lever 1398 which is selectively operable by a handle 1400. The lever 1398 is selectively operable by a lever 1406 which is selectively operable by a handle 1408. The lever 1406 is selectively operable by a lever 1412 which is selectively operable by a handle 1414. The lever 1412 is selectively operable by a lever 1418 which is selectively operable by a handle 1420. The lever 1418 is selectively operable by a lever 1426 which is selectively operable by a handle 1428. The lever 1426 is selectively operable by a lever 1432 which is selectively operable by a handle 1434. The lever 1432 is selectively operable by a lever 1438 which is selectively operable by a handle 1440. The lever 1438 is selectively operable by a lever 1446 which is selectively operable by a handle 1448. The lever 1446 is selectively operable by a lever 1452 which is selectively operable by a handle 1454. The lever 1452 is selectively operable by a lever 1458 which is selectively operable by a handle 1460. The lever 1458 is selectively operable by a lever 1466 which is selectively operable by a handle 1468. The lever 1466 is selectively operable by a lever 1472 which is selectively operable by a handle 1474. The lever 1472 is selectively operable by a lever 1478 which is selectively operable by a handle 1480. The lever 1478 is selectively operable by a lever 1486 which is selectively operable by a handle 1488. The lever 1486 is selectively operable by a lever 1492 which is selectively operable by a handle 1494. The lever 1492 is selectively operable by a lever 1498 which is selectively operable by a handle 1500. The lever 1498 is selectively operable by a lever 1506 which is selectively operable by a handle 1508. The lever 1506 is selectively operable by a lever 1512 which is selectively operable by a handle 1514. The lever 1512 is selectively operable by a lever 1518 which is selectively operable by a handle 1520. The lever 1518 is selectively operable by a lever 1526 which is selectively operable by a handle 1528. The lever 1526 is selectively operable by a lever 1532 which is selectively operable by a handle 1534. The lever 1532 is selectively operable by a lever 1538 which is selectively operable by a handle 1540. The lever 1538 is selectively operable by a lever 1546 which is selectively operable by a handle 1548. The lever 1546 is selectively operable by a lever 1552 which is selectively operable by a handle 1554. The lever 1552 is selectively operable by a lever 1558 which is selectively operable by a handle 1560. The lever 1558 is selectively operable by a lever 1566 which is selectively operable by a handle 1568. The lever 1566 is selectively operable by a lever 1572 which is selectively operable by a handle 1574. The lever 1572 is selectively operable by a lever 1578 which is selectively operable by a handle 1580. The lever 1578 is selectively operable by a lever 1586 which is selectively operable by a handle 1588. The lever 1586 is selectively operable by a lever 1592 which is selectively operable by a handle 1594. The lever 1592 is selectively operable by a lever 1598 which is selectively operable by a handle 1600. The lever 1598 is selectively operable by a lever 1606 which is selectively operable by a handle 1608. The lever 1606 is selectively operable by a lever 1612 which is selectively operable by a handle 1614. The lever 1612 is selectively operable by a lever 1618 which is selectively operable by a handle 1620. The lever 1618 is selectively operable by a lever 1626 which is selectively operable by a handle 1628. The lever 1626 is selectively operable by a lever 1632 which is selectively operable by a handle 1634. The lever 1632 is selectively operable by a lever 1638 which is selectively operable by a handle 1640. The lever 1638 is selectively operable by a lever 1646 which is selectively operable by a handle 1648. The lever 1646 is selectively operable by a lever 1652 which is selectively operable by a handle 1654. The lever 1652 is selectively operable by a lever 1658 which is selectively operable by a handle 1660. The lever 1658 is selectively operable by a lever 1666 which is selectively operable by a handle 1668. The lever 1666 is selectively operable by a lever 1672 which is selectively operable by a handle 1674. The lever 1672 is selectively operable by a lever 1678 which is selectively operable by a handle 1680. The lever 1678 is selectively operable by a lever 1686 which is selectively operable by a handle 1688. The lever 1686 is selectively operable by a lever 1692 which is selectively operable by a handle 1694. The lever 1692 is selectively operable by a lever 1698 which is selectively operable by a handle 1700. The lever 1698 is selectively operable by a lever 1706 which is selectively operable by a handle 1708. The lever 1706 is selectively operable by a lever 1712 which is selectively operable by a handle 1714. The lever 1712 is selectively operable by a lever 1718 which is selectively operable by a handle 1720. The lever 1718 is selectively operable by a lever 1726 which is selectively operable by a handle 1728. The lever 1726 is selectively operable by a lever 1732 which is selectively operable by a handle 1734. The lever 1732 is selectively operable by a lever 1738 which is selectively operable by a handle 1740. The lever 1738 is selectively operable by a lever 1746 which is selectively operable by a handle 1748. The lever 1746 is selectively operable by a lever 1752 which is selectively operable by a handle 1754. The lever 1752 is selectively operable by a lever 1758 which is selectively operable by a handle 1760. The lever 1758 is selectively operable by a lever 1766 which is selectively operable by a handle 1768. The lever 1766 is selectively operable by a lever 1772 which is selectively operable by a handle 1774. The lever 1772 is selectively operable by a lever 1778 which is selectively operable by a handle 1780. The lever 1778 is selectively operable by a lever 1786 which is selectively operable by a handle 1788. The lever 1786 is selectively operable by a lever 1792 which is selectively operable by a handle 1794. The lever 1792 is selectively operable by a lever 1798 which is selectively operable by a handle 1800. The lever 1798 is selectively operable by a lever 1806 which is selectively operable by a handle 1808. The lever 1806 is selectively operable by a lever 1812 which is selectively operable by a handle 1814. The lever 1812 is selectively operable by a lever 1818 which is selectively operable by a handle 1820. The lever 1818 is selectively operable by a lever 1826 which is selectively operable by a handle 1828. The lever 1826 is selectively operable by

to about 50 teeth per inch. Preferably the severing device 20 is positioned at an angle of greater than 0° and less than 90° relative to horizontal, more preferably between about 75° and 89° relative to horizontal, most preferably about 85–87° relative to horizontal, thereby facilitating severing of the metallic foil in an upward motion relative to the location of the foil roll, as shown in FIG. 2. So positioning the severing device 20 also minimizes the possibility of injury to the operator of the device, as the sharp teeth of the severing device 20 are pointed downward.

Optionally extending from support arm 15 between its two ends is guide plate 21. Preferably the guide plate 21 is beveled to form a convex surface to facilitate guiding of the metallic foil 50. Extending vertically from the front portion of the base 12 is an optional front support arm 18. The front support arm 18 supports a second guide plate 22, which in cooperation with guide plate 21, assist in directing the foil 50 during the dispensing operation, and over which the metallic foil 50 rests when the dispenser is not in operation. Preferably the guide plate 22 is also beveled to form a convex surface to facilitate guiding of the metallic foil 50. Guide plates 21 and 22 are positioned so as to form therebetween a nip slightly larger than the thickness of the metallic foil. The guide plates are preferably offset as shown, with either the top plate 21 or the bottom plate 22 being closer to the metallic foil roll than the other, so that the nip is formed therebetween at an upward angle in the same general direction as the foil is being pulled by the user. The nip also minimizes the tendency of the foil 50 to roll back onto the foil roll when not in use. The stop 17 ensures that the positioning of guide plate 21 relative to guide plate 22 is constant, thereby ensuring that the size and location of the nip is constant.

The severing device 20 is preferably positioned at a suitable distance from and a suitable height with respect to the metallic foil roll so as to easily enable the operator to sever each piece of foil at the desired length. Positioning the severing device too close to the roll, either in the vertical or horizontal direction, will hinder the ability of the operator to cut a piece of foil at the appropriate length. Preferably the severing device 20 extends a distance of about 5–7 inches, most preferably about 5.5 inches, in the horizontal direction from the center of the cylinder 14, and is about 5–6 inches above the base 12 and preferably extends a distance of about 2–4 inches, preferably about 3 inches, in the vertical direction from the center of the cylinder 14.

Support arm 15 can optionally include means for supporting one or more mixing bowls 60. To that end, FIGS. 1 and 2 show a plurality of hollow tubes 30 coupled to the top of support arm 15. The inner diameter of each hollow tube is sufficient to receive the handle 61 of a bowl 60, and is deep enough to stabilize and support the weight of the bowl 60 in a substantially horizontal position even when filled with liquid. As shown in FIG. 2, the plurality of hollow tubes is substantially centrally located relative to the base, thereby minimizing the additional space necessary to accommodate the mixing bowls 60. In addition, since the mixing bowls are elevated from the base, valuable counter or cart space is not unnecessarily occupied by the mixing bowls.

FIGS. 8–10 illustrate an improvement of the embodiment of FIGS. 1–3. Specifically, foil folding means 80 is strategically located with respect to the severing device 20 so as to assist in folding the foil about the tail of a rat tail comb. One suitable means of so locating the foil folding means 80 is by fixing it underneath support arm 15 by any suitable means, such as welding. Alternatively, the foil folding means 80 could extend from the same portion of support arm 15

that holds the severing device 20. The foil folding means 80 is preferably a beveled plate, with portion 81 being coupled to the support arm 15, and beveled portion 82 extending from portion 81 towards severing device 20 both in the horizontal and vertical direction. Beveled portion 82 terminates in a downwardly extending angled flange 83, thereby forming a notch 84 at the intersection between beveled portion 82 and the flange 83. Preferably the notch 84 is curved so as to facilitate receipt of the generally cylindrical tail of a rat tail comb. The angle and length of the beveled portion should be such so as to ensure that the notch 84 is positioned above (in the vertical direction) the severing device 20. Preferably the notch 84 is about $1/16$ – $1/8$ of an inch above the severing device 20, and about 0.75–1.25 inches, preferably about 1 inch, behind the severing device 20 (in the direction towards roll 50). The distance between the notch 84 and the severing means 20 will define the amount of the sheet material that is folded about the tail of the comb 70. The width of foil folding means 80 is preferably thinner than the width of the foil 50. For example, where 5 inch wide foil 50 is used, the width of the portion 81, beveled portion 82 and flange 83 is 4 inches in order to allow easy access thereto.

FIGS. 9 and 10 illustrate the operation of the foil folding means 80. The tail of a rat tail comb is positioned underneath the free end of the foil 50. Together with a rat tail comb 70, the free end of the foil 50 is then grasped (such as with the middle finger of the user; the index finger and thumb of the user being used to hold the comb 70 as shown in FIG. 9) at a point about 1 inch from the free end and directed up towards the notch 84. The tail of the comb 70, now with the foil wrapped around it, is brought into contact with the notch 84, creasing the foil 50 about the tail of the comb 70 as shown. This helps minimize slippage of the foil about the comb as the operation continues. The comb is then lowered to a position slightly below the severing device 20, and then brought outwardly past the severing device 20 as shown in FIG. 10, pulling the foil 50 with it. Once the desired length of foil 50 is achieved, an upward motion is then used to sever the foil against the severing device 20 as shown.

FIG. 4 shows a second embodiment of the present invention. A base portion 12' is similar to the base portion 12 of the first embodiment, and includes opposite side walls 40', 41' on which the metallic foil roll is rotatably mounted. A front support arm 18' extends from the base portion 12', preferably at an angle (about 60° relative to horizontal), and terminates at its end distal from the base portion in a severing device 20' having a plurality of sharp teeth as described above. The severing device 20' is positioned at an upward angle of greater than 0° and less than 90° relative to horizontal, preferably 30–50° relative to horizontal more preferably about 40° relative to horizontal. Extending substantially horizontal from the support arm 18' just below the severing device 20' is a resting plate 22' on which the metallic foil 50' rests when the device is not in operation. The resting plate 22' helps prevent the free end of the foil 50' from falling towards the base portion or from its tendency to roll back on the roll of foil, thereby facilitating its access to the operator when the next piece is desired. Alternatively, the guide plates 21 and 22 could be employed in the device of this embodiment, such as by the addition of support arms analogous to arms 15 and 8 of FIGS. 1 and 2.

The opposite side walls 40', 41' include flanges 44 into which the handles of the mixing bowls can be removably stabilized or secured.

FIGS. 6 and 7A, B and C show a third embodiment of the present invention, and can best be described as a hybrid of

both the first and second embodiments. Specifically, it is similar to the embodiment of FIG. 1 in that it includes first and second offset guide plates 21 and 22, as well as support arm 15 having a plurality of hollow tubes 30 (not shown) for supporting mixing bowls 60, and base portion 12 with side walls 40 and 41. It differs from the FIG. 1 embodiment in that the severing device 20 is not coupled to the support arm 15, but rather to a separate angled arm 45 extending outwardly and upwardly from the base portion 12 in front of front support arm 18 that supports guide plate 22. The severing device 20 is angled upwardly as in the embodiment of FIG. 4, which requires that the sheet material be torn with a downward force as in the embodiment of FIG. 4.

Situated between guide plate 22 and severing device 20 is a detent mechanism 55, which serves a purpose similar to the foil folding means 80 of the embodiment of FIG. 8. The detent mechanism 55 can be attached to the apparatus by any suitable means, such as by welding to guide plate 22. It can also be movable and removable, such as by attachment in an optional slot 54 formed near the edge of guide plate 22. This movability feature allows the detent mechanism to be appropriately positioned more toward the left or right of the apparatus, depending upon whether the stylist is left-handed or right-handed, or in the center if desired. In the preferred embodiment, the detent mechanism is permanently fixed to the guide plate 22 and is centrally located relative to the width of the guide plate 22 or severing means 20. The detent mechanism 55 is shaped so that a nadir or indent 56 is formed along its width. This indent 56 is preferably located about 1 inch behind the severing means 20 (toward the guide plate 22), and provides a resting place for the tail of a rat tail comb 60 (FIG. 7B) as the stylist is set to grasp the foil 50 positioned over the mechanism 55. The indent 56 facilitates the proper placing of the comb over the foil, advantageously also creating a crease in the foil about which the foil can be folded onto the comb once severed from the roll. In the embodiment shown, the detent mechanism 55 includes two convex surfaces 55a and 55b, positioned before and after the indent 56 (in the direction toward severing device 20). The shape of these surfaces causes the tail of the rat tail comb to be guided into the indent 56 even if initially placed in a crooked fashion or not directly in the indent. Other suitable shapes accomplishing the same goal could be used, such as sloped portions together forming a triangle or "V" shape.

In either the embodiment of FIGS. 1, 4 or 6, the base 12 could be readily modified to accommodate a plurality of separate rolls of sheet material 50, each being a different thickness and/or color. Different colored sheet material can be used by the beautician to mark different locks of hair in order to identify different colors applied to different locks, or degrees of shading thereof.

In operation, the support arm 15 is raised to expose the cylinder 14 (FIGS. 3 or 6), and a roll of metallic foil 50 or the like is placed on the cylinder 14, which in turn is secured to the base portion 12. The support arm 15 is then returned in its operating position as shown in FIG. 1. The free end of the metallic foil or other sheet material is threaded through the guide plates 21, 22 (when present). When the beautician is ready for a sheet of foil for placement under a lock of hair, the beautician grasps the free end of the foil, either directly with the hand or preferably with the tail 71 of a conventional rat tail comb 70, as shown in FIGS. 2, 7A and 9. When a rat tail comb is used, the beautician grasps the foil at a location about 0.5 to 1.5 inches, preferably about 1 inch, from the free end (FIGS. 2, 7B and 9). The beautician then pulls the foil 50 away from the roll to expose the desired length (FIGS. 7C and 10), and then imparts an upward force (in the

case of the embodiment in FIGS. 1 and 8) to the foil 50 so as to cause the foil to engage against the severing device 20 and sever the foil 50 from the roll. A corresponding downward force would be applied in the case of the embodiment of FIGS. 4 or 6, and the stylist imparts a "flick of the wrist" action so that the wrist is turned 180° with the thumb now pointed downward in order to complete the fold of the foil about the comb.

The severed piece of foil 50 is now positioned in a folded manner (fold 51 shown in FIGS. 2, 5, 9 and 10) on the rat tail comb 70 in a manner conducive to be readily applied under the lock of hair with little or no further manipulation necessary. The fold 51 is preferable to provide additional strength to the upper edge of the foil 50 for proper placement under the lock of hair and against the scalp. As discussed above, facilitation of the fold can be accomplished with foil folding means 80 or detent mechanism 55. Once the foil 50 is so applied to the hair, the rat tail comb is removed while the foil is held in place and the hair is painted or otherwise treated.

The flexibility achieved through using the present device allows various lengths of sheet material to be severed, depending upon the length of the lock of hair being treated. In addition, a single sheet can be used to color or highlight 25 a single lock of hair a plurality of different tones or colors; the end of the lock can be colored or highlighted with a first color, wrapped in the foil and thereby separated from the remaining portion of the lock, which can in turn then be colored or highlighted in a different tone or color, etc. The 30 device enhances productivity, as the beautician never has to put down the comb, and the conventional method of cutting strips of foil at predetermined lengths is no longer needed.

What is claimed is:

1. A dispenser for sheet material, comprising a housing, a 35 roll of sheet material rotatably secured in said housing, sheet material severing means attached to said housing for severing said sheet material, said severing means being positioned at an angle of greater than 0° and less than 90° with respect to horizontal, and a detent mechanism attached to said housing, said detent mechanism configured to fold said sheet material upon contact with said sheet material.

2. The dispenser of claim 1, further comprising guide means coupled to said housing for guiding said sheet material from said roll toward said severing means.

3. The dispenser of claim 2, wherein said guide means comprises a pair of plates extending from said housing and forming a nip therebetween.

4. The dispenser of claim 1, further comprising means coupled to said housing for supporting at least one bowl.

5. The dispenser of claim 1, further comprising a support arm having a first end movably coupled to said housing and a second end spaced from said first end and terminating in said severing means.

6. The dispenser of claim 1, further comprising foil folding means located between said roll of sheet material and said severing means.

7. The dispenser of claim 5, further comprising foil folding means coupled to said support arm, said foil folding means comprising a beveled plate terminating in a flange and forming a notch therebetween.

8. The dispenser of claim 1, wherein said sheet material is aluminum foil.

9. A dispenser for sheet material, comprising a housing, a roll of sheet material rotatably secured in said housing, sheet material severing means attached to said housing for severing said sheet material, said severing means being positioned at an angle of greater than 90° and less than 180° with

respect to horizontal, guide means attached to said housing for guiding said sheet material from said roll toward said severing means, and a detent mechanism between said guide means and said severing means, said detent mechanism configured to fold said sheet material upon contact therewith.

10. The dispenser of claim 9, wherein said guide means comprises a pair of plates extending from said housing and forming a nip therebetween.

11. The dispenser of claim 9, further comprising means coupled to said housing for supporting at least one bowl.

12. The dispenser of claim 9, wherein said sheet material is aluminum foil.

13. A method of dispensing foil and applying said foil to the hair of an individual, comprising:

providing a dispenser for sheet material, comprising a housing, a roll of sheet material rotatably secured in said housing, and sheet material severing means attached to said housing for severing said sheet material;

grasping said sheet material with a rat tail comb;

pulling said sheet material in a direction away from said roll and past said severing means;

severing said sheet material from said roll by causing said sheet material to engage said severing means and tear; and

contacting said sheet material with said hair.

14. The method of claim 13, wherein said severing means is positioned at an angle of greater than 0° and less than 90° with respect to horizontal.

15. The method of claim 13, wherein said severing means is positioned at an angle of greater than 90° and less than 180° with respect to horizontal.

16. The method of claim 13, further comprising causing said sheet material to fold about said rat tail comb after said sheet material is grasped with said rat tail comb.

17. The method of claim 16, wherein said dispenser further comprises guide means attached to said housing for guiding said sheet material from said roll toward said severing means, and a detent mechanism between said guide means and said severing means having an indentation, and wherein said sheet material is caused to fold about said rat tail comb by placing said rat tail comb over said sheet material and in said indentation of said detent mechanism.

18. The method of claim 16, wherein said dispenser further comprises foil folding means between said roll and said severing means, said folding means comprising a beveled plate terminating in a flange and forming a notch therebetween, and wherein said sheet material is caused to fold about said rat tail comb by bringing said rat tail comb and said grasped sheet material into contact with said notch.
